Primary Examiner — Ian Simmons*Assistant Examiner* — Keith Frank(74) *Attorney, Agent, or Firm* — Fenwick & West LLP(57) **CLAIM**

I claim the ornamental design for a folding container, as shown and described.

DESCRIPTION

FIG. 1 is a perspective view of a folding container in a folded configuration showing my new design.

FIG. 2 is a top plan view thereof.

FIG. 3 is a front elevational view thereof, the rear being a mirror image.

FIG. 4 is a left side elevational view thereof.

FIG. 5 is a right side elevational view thereof.

FIG. 6 is a bottom plan view thereof.

FIG. 7 is a perspective view thereof in an open configuration.

FIG. 8 is a top plan view thereof.

FIG. 9 is a front elevational view thereof, the rear being a mirror image.

FIG. 10 is a left side elevational view thereof, the right side being a mirror image; and,

FIG. 11 is a bottom plan view thereof.

The stipple shading and the straight line shading in the drawings illustrate a contrasting appearance. The broken lines in the drawings illustrate the portions of the folding container that form no part of the claimed design.
